US00D854682S

(12) **United States Design Patent** (10) **Patent No.:** **US D854,682 S**
(45) **Date of Patent:** **** Jul. 23, 2019**

(54) **MEDICAL DEVICE HANDLE**

- (71) Applicant: **The Spectranetics Corporation**, Colorado Springs, CO (US)
- (72) Inventors: **Phillip Charles Halbert**, San Francisco, CA (US); **Christopher Allen Wilson**, Oakland, CA (US)
- (73) Assignee: **THE SPECTRANETICS CORPORATION**, Colorado Springs, CO (US)
- (**) Term: **15 Years**
- (21) Appl. No.: **29/623,926**
- (22) Filed: **Oct. 27, 2017**

Primary Examiner — Wan Laymon

Assistant Examiner — Mark Booker

CLAIM

The ornamental design for medical device handle, as shown and described.

DESCRIPTION

FIG. 1 is a front perspective view of medical device handle illustrating our new design;

FIG. 2 is an enlarged front side view of FIG. 1 thereof;

FIG. 3 is an enlarged back side view of FIG. 1 thereof;

FIG. 4 is a left side view thereof;

FIG. 5 is a right side view thereof;

FIG. 6 is a top view thereof; and,

FIG. 7 is a bottom view thereof.

The portions of the device shown in broken lines form no part of the claimed design. The uncolored portions of the device enclosed by broken lines form no part of the claimed design.

1 Claim, 5 Drawing Sheets

See application file for complete search history.
